UNITED STATES PATENT OFFICE.

ERASTUS H. BARNEs AND ERNEST CLEMENS THORSCHMIDT, OF NEW YORK, N. Y.

MACHINE FOR CORRUGATING, CUTTING UP, AND DRIVING STRIPS OF METAL INTO WOOD.

1,039,478.

Specification of Letters Patent. Patented Sept. 24, 1912.

Application filed March 8, 1906. Serial No. 304,822.

To all whom it may concern:

Be it known that we, ERASTUS H. BARNEs and ERNEST CLEMENS THORSCHMIDT, citizens of the United States, residing at the 5 borough of Brooklyn, in the county of Kings, city and State of New York, have invented a new and useful Improvement in Machines for Corrugating, Cutting Up, and Driving Strips of Metal into Wood.

10 Our invention relates to a machine for joining up parallel strips of wood especially in the manufacture of boxes, and it relates more especially to a machine adapted to receiving a strip of metal of predetermined 15 width,—one edge of which by preference has been sharpened—and first corrugating the strip and then simultaneously cutting up such strip into pieces of a suitable length, which are received one at a time as cut into 20 a hopper in a vertical or edgewise position and are then forced into and across the meeting edges of adjacent pieces of wood for the purpose of joining up parallel strips.

In the device of our invention we employ 25 a pair of meshing corrugated rollers in width about agreeing with the width of the strip of metal to be corrugated. These rollers are in suitable bearings, one set of which are spring-pressed toward the other. Upon 30 the shaft of one of these rollers is a ratchet and a pawl and lever device for feeding the rollers and in connection with said pawl and lever device, we employ means for adjusting the extent of feed so that the desired 35 number of teeth of the ratchet may be taken up with each feed movement. This device is actuated in opposite directions by the vertical movement of a hammer device employed in driving the metal plates into the 40 wood.

We employ a spring returned cutter device for severing the corrugating strip into pieces of predetermined length; the supporting body of the machine carrying these parts 45 having an internal inclined chamber receiving the cut off pieces and down which they move assuming by gravity the desired vertical position beneath the hammer device.

The cutter structure and the hammer device 50 are actuated by a suitable prime mover that forms no part of our present invention, and the movements of these parts are so timed that the driving of one piece of metal and the cutting of another are substantially 55 simultaneous; the feed and corrugating of

the strip being effected on the rising movement of the hammer device and intermediate of the aforesaid movements, all of which is hereinafter more specifically set forth.

In the drawing, Figure 1 is a front elevation and Fig. 2 a side elevation and partial section of the devices constituting our improvement. Fig. 3 is an elevation of the interior parts of the body support with the corrugating rollers and other parts removed, 60 and Fig. 3' is a sectional plan at the dotted line x , x . Fig. 4 is a vertical substantially central section through the corrugating rollers. Fig. 5 is a side elevation of the lever and pawl devices and Fig. 6 is an elevation 70 of the device for adjusting the same separated from the parts shown in Fig. 5.

a represents a suitable fixed bar or support preferably with an undercut groove receiving a rib formed upon the boss b^1 of the 75 supporting body b , there being by preference bolts 2, the heads of which are received in this undercut groove with the stems passing through the rib and the boss b^1 for securing the same and the body to the fixed support. 80 This supporting body, as will be seen from Figs. 2 and 3, is advantageously of rectangular form and provided with suitable channels for the parts that move therein, and b^2 is a plate preferably secured by the bolts 85 3 to one face of the supporting body b . Upon this plate b^2 there are bracket plates c , c^1 supporting corrugating rollers d , e , having shafts d^1 , e^1 therefor. The shaft d^1 of the roller d passes through apertures in 90 these bracket plates c , c^1 , which form bearings therefor.

The shaft e^1 of the corrugating roller e passes through bearing boxes e^2 received in 95 slots formed in the bracket plates c , c^1 ; said bearing boxes being movable vertically in said slots. Beneath these bearing boxes e^2 there are springs 4, supporting screws 5 and set screws 6. The springs 4 normally support the bearing boxes e^2 and while strips already corrugated are being run through 100 to be cut up and driven into the wood. The springs 4 are however perforated for the points of the set supporting-screw 5 to pass through for a positive bearing and hold 105 against the boxes as the parts are employed in this condition when the strip of metal is being corrugated by the rollers d , e . Upon one end of the shaft d^1 of the corrugating roller d there is secured a ratchet wheel f 110

and on the same shaft beyond the ratchet wheel there is a pawl arm and jaw *g* and a cam arm and jaw *h*, the jaws having pivotal interlocking parts the same as a pair 5 of cutting tools where said parts fit upon the end of the shaft *d*¹. (See Figs. 5 and 6.) Upon the pawl arm *g* is a pawl *g*¹ adapted to engage the teeth of the ratchet wheel *f*, a spring acting with the said pawl to hold the 10 toothed end of the pawl into engagement with the teeth of the ratchet wheel *f*, and the supporting body *b* is recessed or hollowed out so as to provide for the swinging movements imparted to the pawl arm *g* and 15 cam arm *h* as hereinafter described.

The jaws of the pawl arm and cam arm are provided with interiorly threaded holes 7, 8 and a lug plate *i* fits over the surface of said jaws as shown in Figs. 1 and 2; said 20 lug plate being provided with an elongated hole for the shaft *d*¹ with side lugs 9 coming outside of the said jaws and with a central lug *i*¹ coming between the jaws,—screws 10 and 11 being employed through the elongated holes in the lug plate passing into the 25 holes 7 and 8 of the said jaws. By this lug plate *i* we adjust the relation of the pawl arm and jaw with the cam arm and jaw so as to take up wear or to regulate the feed 30 imparted, or in other words, the number of teeth of the ratchet wheel *f* to be taken up by the pawl *g*¹ in the movement imparted collectively to the pawl arm *g* and cam arm *h* as hereinbefore described; it being ap- 35 parent that if the lug *i*¹ is forced nearer to the shaft *d*¹ so as to separate the jaws of the pawl arm and cam arm that the angle between said arms, considering a straight line through either arm, will be lessened or in 40 other words, the arms brought closely together, consequently with a given amount of movement imparted to said structure a greater number of teeth of the ratchet wheel will be taken up.

45 We provide a hammer bar *l*, a hammer blade *l*¹ and a hammer head *l*²; the bar moving through a groove in the body *b*, the head upon the upper end of the blade to be struck by any suitable instrumentality in 50 operating said hammer bar and the blade *l*¹ projecting through the lower portion of the said supporting body. On the projecting arm or bracket of this hammer blade we secure a roller *m* which comes back of the cam arm *h* and below the pawl arm *g* and we connect the hammer head *l*² with the other end of the hammer blade *l*¹ by any desired means such as the pin shown in Figs. 1 and 2 and any suitable instrumentality may be employed for raising and lowering the said hammer bar, blade and head with the roller *m* to a predetermined extent. With the upward movement of these parts the said roller *m* strikes the under surface of the pawl arm *g* raising the

same and swinging said arm with the pawl *g*¹ and the cam arm *h* and at the same time through the pawl *g*¹ turning the ratchet wheel *f* and the corrugating roller *d* the said cam arm *h* with this movement passing 70 into a recess in the body *b* shown in Fig. 2 by dotted lines. With the downward movement of the said hammer bar, blade, head and roller, the said roller *m* strikes the cam arm *h* and swings the same down out of the 75 recess in the body into the position shown in Fig. 2, returning the pawl arm *g* from its highest position into the inclined position shown in Fig. 2; the pawl meantime running freely over the surface of the teeth of the ratchet *f*. 80

For the purpose of preventing any lost motion or accidental movement of the corrugating roller *d* and by it the roller *e* we provide a friction device for engaging the 85 end of the shaft *d*¹ which projects beyond the bracket plate *c*¹. This friction device comprises a clamp arm *s* having an opening receiving the end of the shaft, a securing screw 22 for connecting this clamp device 90 to the side of the bracket, and the clamp arm is split and a clamping screw 21 employed for either drawing together the split portion of the arm to produce a friction on the end of the shaft *d*¹ or to release and 95 modify said frictional hold and by this means any accidental movement of this shaft *d*¹ and its roller *d* is prevented.

Referring to Fig. 3, we provide in the supporting body *b* recesses 12, 13 and 14; 100 the recess 12 receiving the pawl arm *g* and pawl *g*¹, the recess 13 receiving the cam arm *h* and the recess 14 providing for receiving the corrugating strips of metal and the pivoted dog *k*, the upper surface of which 105 forms an incline down which said corrugated strips of metal pass after being cut from the strip as corrugated. This pivoted dog *k* is connected by pivot screw *k*¹ to the body *b* and the spring *k*² between said body 110 and the lower portion of said dog serves to keep the edge of the dog adjacent to the hammer blade or with the opposite surface of the body when the hammer blade is re- 115 tracted, the same yielding as the hammer blade is projected.

In Fig. 2 the corrugated fastening strip is represented at 15 as having been driven by the hammer device into the edges of adjacent pieces of wood 16 across their meeting edges. 120

Referring particularly to Figs. 3 and 4 *n* represents the cutter bar, *o* a yoke frame with a head portion *o*¹ recessed to receive 125 the cutter bar *n* in a channel provided therefor in the body *b*; there being a groove 17 in the back portion of the yoke frame *o* and an interiorly threaded hole in the cutter bar to receive an off-set screw stem *n*¹,—in fact 130

this screw n^1 is provided with two off-set portions or shoulders one adjacent to the threaded reduced end which passes into the cutter bar n , and the other shouldered portion which extends across the face of the groove 17 comes against the same, and the screw is thus set up to position so as to bind the yoke frame o and the cutter bar n firmly together with the idea of causing them to move in unison. We provide in a recess in the upper end of the yoke frame o a screw 18, the head of which seats on the shouldered portion of the cutter bar n , and the head o^1 of the yoke frame is formed with side 10 prolongations beneath which come the springs 19 which yield when the cutter bar structure is forced downward by any instrumentality and which when pressure is released on the cutter bar device return 15 same to an initial position. We provide a cutter bed or shear arm r (see Fig. 1) set in an inclined position in a recess in the back face of the plate b^2 and secured in position by a locking nut 20 which when loosened 20 provides for setting up this cutter bed in the desired position or for removing the same so as to re-grind or true its cutting edge.

In the operation of the device of our improvement the strip of metal to form the fastening device is preferably made with one edge sharpened and the same is introduced into the machine between the corrugating rollers d , e . These are rotated as 30 heretofore described to a predetermined extent by the vertical movement of the hammer devices and the roller carried thereby acting upon the pawl arm g and cam arm h and the cutter devices are actuated and 35 timed with the corrugation of a strip of predetermined length so as to cut off this strip between the lower edge of the cutter bar n and the upper edge of the cutter bed or shear r . The cut strip then falls over the 40 upper edge k^3 or shoulder of the dog k being tipped thereby and moves down over the inclined upper face of said dog in the recess 45 until it strikes the hammer blade l^1 . The movement of the said hammer devices 50 and the actuation by them of the feeding devices for further corrugating the strip of metal retracts the hammer blade l^1 and the lower end of the dog k moved by the spring k^2 follows the hammer blade as retracted 55 and closes against the opposite face of the body. The cut strip forming the fastener device then further descends by gravity and comes into a substantially vertical position beneath the lower end of the hammer blade 60 l^1 . The two pieces of wood 16, 16, to be connected are laid on a suitable support so that their adjacent edges occupy a position transversely to the line of the hammer blade and so that their surfaces come closely adjacent 65 to the projecting portions or lips b^8 on the body b and dog k . The next movement of the hammer devices forces this fastening device or corrugated piece of metal 15 down into the pieces of wood as shown in Fig. 2, and simultaneously returns the pawl arm 70 and cam arm to the position shown in Fig. 2 preparatory to another feed and with this return movement the cutter devices are actuated to sever the corrugated strip to form another fastening piece. We provide in the 75 supporting body of the machine and at the back of the recess receiving the corrugated strip of metal d^2 a bar t fitting against an off-set or shoulder of the supporting body and secured thereto by one or more screws 80 23 and to this bar a plate t^1 is pivoted; said bar t and plate t^1 being in parallel vertical planes with an intervening spring 24 placed horizontally and the plate t^1 having a tilting function on its pivotal connection to the bar. 85 We also provide a guide plate u occupying a horizontal position and forced into the supporting body b with its ends in grooves 25. In the further operation of the machine and in the event of the failure of the cutter device to cut off a strip and the feed of the other corrugated strip d^2 in the machine this pivoted plate t^1 as a door yields and permits the corrugated strip to pass through above 90 the same and beneath the guide plate u , because if a double length of the fastener device is cut off in the machine the recess 14 would not receive it and in such event the double length strip passes out into the recess in the back of the machine above the fixed 95 supporting bar a where it is visible and may be removed by hand so as not to impede the further movements of the machine. In the left hand edge of the hammer bar l we provide a groove 26 and place therein a block 27 and employ a screw 28 passing through the body b into the block 27 to hold the block in place causing the same to both act as a 100 guide for the reciprocating hammer bar l and to retain the same in position in the 105 body b .

We claim as our invention:

1. The combination with devices for deflecting and thus corrugating a strip of sheet metal, of devices for cutting said strip into suitable lengths and thereby forming fastening plates, and devices for driving the cut up strips or fasteners successively and edge-wise in the line of the corrugations into wood.
2. The combination with devices for corrugating a strip of metal and means for actuating said devices whereby the strip is simultaneously corrugated and fed, of devices for cutting said strip into suitable 115 lengths and thereby forming fastening plates and devices for driving the cut up strips or fasteners successively and edge-wise in the line of the corrugations into wood.
3. The combination with devices for corrugating a strip of metal and means for actuating said devices whereby the strip is simultaneously corrugated and fed, of devices for cutting said strip into suitable 120 lengths and thereby forming fastening plates and devices for driving the cut up strips or fasteners successively and edge-wise in the line of the corrugations into wood.

3. The combination with devices for corrugating a strip of metal and means for actuating said devices whereby the strip is simultaneously corrugated and fed, of devices for cutting such strip into suitable lengths and thereby forming fastening plates, devices for regulating the length of the cut up strips and other devices for driving the cut up strips or fasteners successively and edgewise in the line of the corrugations into wood.
4. The combination with a supporting body of metal and associated supporting parts, of a pair of corrugating rollers for corrugating a strip of metal, a cutter device and cutter bed for severing the corrugated strip into suitable lengths and thereby forming fastening plates, devices providing for feeding a cut up strip at a time and a hammer device for driving the said cut up strips or fasteners successively and edgewise in the line of the corrugations into wood.
5. In a machine for corrugating, cutting up and driving strips of metal into wood, the combination with a pair of corrugating rollers, shafts and bearings therefor, of a ratchet and pawl device upon the shaft of one of said rollers for rotating the same, a cam arm co-acting with the pawl device and a vertically movable device for acting upon the pawl device and the cam arm successively for effecting the feed of the corrugating rollers.
6. In a machine for corrugating, cutting up and driving strips of metal into wood, the combination with a pair of corrugating rollers, shafts and bearings therefor, of a ratchet and pawl device upon the shaft of one of said rollers for rotating the same, a cam arm co-acting with the pawl device, a hammer device movable vertically, a roller carried thereby and adapted to act successively upon the pawl device and the cam arm to shift the position of said parts in effecting the movement of the corrugating rollers and the feed of the corrugated strip.
7. In a machine for corrugating, cutting up and driving strips of metal into wood, the combination with a pair of corrugating rollers, shafts and bearings therefor, of a pawl arm and jaw, a cam arm and jaw, said jaws being perforated and interlocking and mounted upon the shaft of one of the corrugating rollers, a ratchet mounted upon the same shaft of the corrugating roller, a spring controlled pawl mounted on the pawl arm and engaging the teeth of the ratchet, means for controlling the associated relation of the said pawl arm and cam arm, a vertical movable hammer device and a roller thereon adapted to successively contact with the pawl arm and cam arm for actuating the ratchet and pawl device and for revolving the corrugated rollers and feeding the strip.
8. In a machine for corrugating, cutting up and driving strips of metal into wood, the combination with a pair of corrugating rollers, shafts and bearings therefor, of a pawl arm and jaw, a cam arm and jaw, said jaws perforated and interlocking and mounted upon the shaft of one of the corrugating rollers, a ratchet mounted upon the same shaft of the corrugating roller, a spring controlled pawl mounted on the pawl arm and engaging the teeth of the ratchet, a lug plate having an elongated opening and adapted to fit over the same shaft of the corrugating roller, said lug plate having opposite edge lugs and a central lug, the central lug coming between the jaws and the edge lugs outside the jaws and said lug plate adapted for a radial movement with reference to said shaft so as to increase or lessen the opening between said jaws, devices for securing the lug plate in position, a vertical movable hammer device and a roller thereon adapted to successively contact with the pawl arm and cam arm for actuating the ratchet and pawl device and for revolving the corrugated rollers and feeding the strip.
9. In a machine for corrugating, cutting up and driving strips of metal into wood, the combination with a supporting body having an inclined recess 14 and a cutter bar, of a pivoted dog having an inclined outer surface received in said recess, a spring for maintaining the normal position thereof and an edge or shoulder k^3 at the upper end thereof and an adjacent cutter bed 100 or shear.
10. A machine having suitable combined devices for corrugating, cutting up and driving strips of metal into wood, a supporting body, the cutter bar and cutter bed, a bar t , a plate t^1 pivoted thereto in a recess of the supporting body in line with the corrugating movement of the strip, a spring for normally holding the pivoted plate in position and a guide plate beneath which the 110 corrugating strip passes.
11. A machine having suitable combined devices for corrugating, cutting up and driving strips of metal into wood, the corrugating devices comprising corrugating rollers, 115 their shafts and bearings, a ratchet mounted upon the shaft of one of said rollers, a pawl for engaging and moving the said ratchet, devices mounted upon the same shaft as the ratchet and having a pivotal relation thereon, one of which devices carries the said pawl and a device co-acting with the aforesaid devices and having an adjustable relation thereto whereby the extent of movement imparted to the pawl may be varied at the pleasure of the operator, and a device for actuating said adjustable parts and the pawl.
12. A machine having suitable combined devices for corrugating, cutting up and 130

- driving strips of metal into wood, the corrugating devices comprising a pair of corrugating rollers, their shafts and bearings therefor, a ratchet mounted on the shaft of 5 one of said rollers, a pawl arm and jaw and a pawl carried thereby and engaging the teeth of the ratchet, the cam arm and jaw, said jaws being perforated and mounted upon the same shaft as the said ratchet and 10 interlocking and a device associated with the pawl arm and cam arm and their jaws and having a radial movement with relation to the same shaft of the corrugating roller and means for securing said device to the said 15 jaws for adjustably fixing the relation of said jaws to one another to control the extent of movement imparted to the said ratchet by the pawl, and a device for actuating said adjustable parts and the pawl.
- 20 13. A machine having suitable combined devices for corrugating, cutting up and driving strips of metal into wood, a supporting body having an opening recess or cavity therein in line with the corrugating feed 25 of the strips of metal, means for guiding the strip as corrugated and a yielding device secured to said supporting body in the line of feed and which when the strip fails to be cut permits the corrugated strip to pass through 30 the said supporting body to the rear where the failure to cut up the strip is made apparent and the piece may be removed.
14. In a machine of the class specified, the combination of automatic means for 35 forming transverse corrugations in a rectangular sheet metal fastener, suitable means for receiving and holding the finished fastener in position for edgewise insertion, and driving mechanism for engaging the 40 ends of the corrugations to insert the same endwise.
15. In a machine of the class specified, the combination of a combined corrugating and feeding mechanism adapted to form 45 transverse corrugations in a strip of sheet metal and feed the same forward in the direction of its length a cutting mechanism for cutting off lengths of said transversely corrugated strip of sheet metal, a driving 50 mechanism for engaging the ends of the said corrugations to insert each finished fastener edgewise, and means for guiding the said transversely corrugated strip of sheet metal to the said cutting and driving means.
- 55 16. In a machine of the class specified, adapted for making and driving corrugated sheet metal fasteners, the combination of means for first forming transverse corrugations in the strip of sheet metal, means for 60 then cutting off a suitable length of said strip of corrugated sheet metal, means for finally driving the sheet metal edgewise and in a direction to insert the corrugations endwise, and suitable operating connections by 65 which the corrugating and cutting and driv-

ing operations are performed on each fastener, in the order mentioned, and means for at will varying the number of corrugations for each fastener.

17. In a machine of the class specified, 70 adapted for making and driving corrugated sheet metal fasteners, the combination of automatic means for feeding a transversely corrugated strip of sheet metal, automatic means for cutting off a suitable length of the strip of sheet metal thus fed in a direction crosswise of its transverse corrugations, means for driving the sheet metal fasteners edgewise and in a direction to insert the corrugations endwise, and suitable connections 75 by which the feeding and cutting and driving operations are performed on each transversely corrugated fastener in the order mentioned, and means for at will varying the number of corrugations for each fastener. 80

18. In a machine of the class specified, the combination of a combined corrugating and feeding mechanism adapted to form transverse corrugations in a strip of sheet metal 90 and feed the same forward in the direction of its length; a cutting mechanism for cutting off lengths of said transversely corrugated strip of sheet metal, a driving mechanism for engaging the ends of the said corrugations to insert each finished fastener edgewise; and means for guiding the said transversely corrugated strip of sheet metal to the said cutting and driving means, and means for at will varying the number of corrugations for each fastener. 95

19. A machine for making and driving corrugated sheet metal fasteners by inserting the fasteners edgewise in the line of their corrugations, comprising mechanism 100 for driving the said fasteners, and automatic mechanism in said machine for providing or forming a plurality of transverse corrugations on each fastener before it is driven.

20. In a machine of the character described, means for feeding a metal strip, means for varying said feed, to produce fasteners of different widths, means for severing a fastener from said strip, and means for driving the fastener edgewise. 110

21. In a machine of the character described, the combination with a support for the material to be joined, of means for feeding a metal strip, means for varying said feed to produce fasteners of different widths, 120 means for severing the end of said strip, means for holding said severed end, and means for forcing said severed end edgewise from said holding means and into the material aforesaid.

22. In a machine of the character described, the combination with a support for the material to be joined, of means for imparting a step-by-step movement to a metal strip, means for varying the extent of such 130

movement, to produce fasteners of different widths, means for successively severing the ends of said strip, means for holding said severed ends, and means for forcing said 5 severed ends edgewise from said holding means and into the material aforesaid.

23. In a machine of the character described, the combination with a support for the material to be joined, of means for receiving one end of a metal strip, means for feeding said strip with a step-by-step movement, means for varying the extent of said movement, to produce fasteners of different widths, means for successively severing the 10 ends of said metal strip, means for holding said severed ends, and means for forcing said severed ends edgewise from said holding means and into the material aforesaid.

24. In a machine of the character described, the combination with a support for the material to be joined, of means for receiving one end of a metal strip, means for feeding said strip with a step-by-step movement, means for varying the extent of said 20 movement to produce fasteners of different widths, a cutting device for severing the end of said strip as it is advanced, means for holding said severed end, and means for forcing said severed end edgewise from said 25 holding means, and into the material aforesaid.

25. In a machine of the character described, the combination with a support for the material to be joined, of a transverse 30 support arranged above said support having arranged thereon a feeding device adapted to advance one end of a metal strip, means for varying the amount of said strip advanced, a chuck arranged adjacent to said 35 feeding device adapted to receive the end of said strip, a cutting device adapted to sever the end of said strip within said chuck, spring-actuated means for holding the sev-

ered end of said metal strip longitudinally in a horizontal position within said chuck, 45 and means for forcing said severed end edgewise from said chuck, and into the material to be joined.

26. In a machine of the class specified, adapted for making and driving corrugated 50 sheet metal fasteners, the combination of automatic means for first forming transverse corrugations in the strip of sheet metal, automatic means for then cutting off a suitable length of said strip of corrugated sheet 55 metal, automatic means for finally driving the sheet metal edgewise and in a direction to insert the corrugations endwise, and suitable operating connections by which the corrugating and cutting and driving operations 60 are performed on each fastener in the order mentioned.

27. In a machine of the character described, the combination with a support for the material to be joined, of a transverse 65 support arranged above said support having arranged thereon a feeding device adapted to advance a metal strip, means for adjusting said feeding device to vary the extent of the feed, a chuck arranged adjacent 70 to said feeding device adapted to receive one end of said strip, a cutting device adapted to sever the end of the strip within said chuck, means for holding the severed end of said strip longitudinally in a horizontal position 75 within said chuck, and means for forcing said severed end edgewise from said chuck, and into the material to be joined, substantially as specified.

Signed by us this 3d day of March 1906. 80
